UNITED STATES PATENT OFFICE.

ELLSWORTH L. KNIGHT, OF COALDALE, WEST VIRGINIA, ASSIGNOR OF ONE-HALF TO HENRY W. RAWSON, OF COOPERS, WEST VIRGINIA.

ANTICREEPER AND BRACE FOR RAILWAY-RAILS.

No. 844,145.

Specification of Letters Patent.

Patented Feb. 12, 1907.

Application filed September 13, 1906. Serial No. 334,494.

To all whom it may concern:

Be it known that I, ELLSWORTH L. KNIGHT, a citizen of the United States of America, residing at Coaldale, in the county of Mercer and State of West Virginia, have invented new and useful Improvements in Anticreepers and Braces for Railway-Rails, of which the following is a specification.

This invention relates generally to rail ties and fastenings, and particularly to means for bracing the rails from lateral movement and preventing creeping or longitudinal movement thereof under the strains falling thereon from the passage of rolling-stock.

The main object of the invention is to provide simple, safe, and inexpensive means for fastening the rail in position at points where it is subjected to great lateral strain, and at the same time holding the rail so securely as to effectually prevent it from creeping.

A further object of the invention is to provide a construction of rail support, brace, and fastening which is adjustable to compensate for wear and operative to securely fasten the rail to a tie as well as to firmly fasten the rail to the supporting parts, so that longitudinal movement of the rail in either direction cannot possibly occur.

In the accompanying drawings, Figure 1 is a perspective view showing the application of the invention. Fig. 2 is a horizontal transverse section through the rail and applied parts of the invention. Fig. 3 is a transverse section of the brace-block. Fig. 4 is a perspective view of the spring locking-key.

Referring to the drawings, 1 designates a tie, and 2 a rail of conventional construction, and 3 a chair or support for the rail. This chair comprises an angular anchor-plate 4, embodying a horizontal flange 5 to rest upon the upper surface of the tie, and a vertical flange 6 to bear against one of the sides of the tie, said plate being arranged longitudinally of the tie and transversely of the rail, as clearly shown in Figs. 1 and 2. From the flange 5 projects a supporting plate or extension 7, which extends beneath the base of the rail and forms an extended support therefor, the said extension being provided adjacent its opposite side edges with openings 8 for the passage of the spikes 9, which secure the rail to the tie and assist in fastening the chair in

position. The inner faces of the anchor-plate and its extension are preferably provided with spurs, serrations, or equivalent means 10 to sink into the tie and act as supplemental means to prevent the chair from shifting thereon.

Formed upon or suitably secured to the flange 5 of the anchor-plate are clips 11 and 12, which are bent or curved upwardly and inwardly to respectively overhang the adjacent flanges of the rail-base, the clip 11 being arranged to bear upon the base and provided with a supporting-plate 13, projecting beneath the same, while the clip 12 is normally spaced from the adjacent side and flange of the base and projects upward some distance above the latter.

A brace-block 14 is provided to bear upon the web and flange of the rail on the side opposite the clip 11 and to fit partially within the clip 12. This block has its inner face conforming substantially in contour to the rail-base and web and is arranged to bear at its upper end against the head of the rail to brace the same against outward and downward pressure. The lower portion of the block is recessed to receive and embrace the adjoining flange of the rail-base and is provided with a supporting-plate 15 to project inwardly beneath the same and to co-operate with the plate 13 to form a seat for the rail. The block is further provided with a shoulder 16 to bear against the under side of the overhanging portion of the clip 12, the outer face of said block being formed with a semi-circular recess operating in conjunction with the correspondingly-shaped portion of the body of the clip 12 to form a tapered socket for the reception of a tapered plug or key 17, provided at its reduced end with a threaded stem 18, carrying a spring-washer 19 and an adjusting-nut 20 to adjustably hold it in position. This plug or key serves to hold the brace-block in bearing engagement with the rail and to crowd the latter against the clip 11, thus securely tying and fastening the rail against both lateral and longitudinal movement. This form of the key and construction of the clip 12 and brace-block permits of the adjustment of the key to force the block farther inward when occasion requires to compensate for wear and to always maintain a tight connection between the parts.

In order to insure further safety in holding

the rail against longitudinal or creeping movement, a spring-key 21 is provided for use within the clip 11 and between the same and edge of the adjacent flange of the rail-base. 5 This key fits in a notch or recess 21^a in said clip and is provided with terminal teeth or biting portions 22, adapted to engage said flange, and is longitudinally curved or of arcuate form, so as to bend under the pressure of the 10 rail when the latter is crowded toward the clip 11 by the brace-block, so that the teeth will sink to a greater extent into the rail and more firmly lock the same against movement, the yielding action of the key also providing 15 for the automatic adjustment of said key to compensate for adjustments of the rail through the action of the tapered plug in exerting varying degrees of pressure on the bracing-block.

20 The key 21 is of greater length than the recess 21^a and its bowed body portion is adapted to move inward under pressure until the center of its convex side comes into contact with the inner vertical wall of the recess, 25 whereby its inward movement is limited. The toothed ends 22 of the key project beyond the end walls 22^a of the recess and are adapted when pressure falls thereon to bear upon said walls, which serve as stops to limit 30 their upward movement, thus holding them firmly in engagement with the rail. By this mode of mounting the key within the recess or notch 21^a the key is held from displacement and is therefore adapted to effectually 35 supplement the action of the clamping means to prevent longitudinal creeping of the rail.

It will be understood that the clips 11 and 12 are respectively arranged on the inner and outer sides of the rail and that the bracing-block consequently sustains and supports the 40 rail against outward pressure, so that the rail, in addition to being held against longitudinal and lateral movement, will be sustained and braced against outward tilting pressure on 45 the head thereof, thus rendering the device of great value in bracing rails at curves.

It will accordingly be seen that the invention provides an anticreeping and bracing fastener which is simple of construction, capable of manufacture at a low cost, and which will securely support the rail against 50 all the strains to which it is subjected in use from the wheels of rolling-stock.

Having thus described the invention, what 55 is claimed as new is—

1. A rail-fastening comprising a chair of T form, the same comprising a horizontal plate adapted to extend transversely under the rail, a vertical web projecting downwardly 60 from the outer edge of said plate and coextensive in length therewith and adapted to bear against one side of the tie on which the plate is seated, and an extension projecting centrally from the opposite side of the plate, 65 said plate and extension being provided with

means for securing a rail thereto and to the tie.

2. A rail-fastening comprising a chair of T form, said chair comprising a horizontal plate adapted to extend transversely beneath the rail, a vertical plate or web depending from one of the sides of said plate and coextensive in length therewith, an extension projecting centrally from the opposite side of the plate and adapted to extend longitudinally beneath the rail, said extension being formed with openings for the passage of a securing-spike, clips upon the horizontal plate, and means associated with said clips for clamping the rail therebetween. 70 75

3. A rail-fastening comprising a chair adapted to be secured to a tie and provided with integral clips, one of said clips being adapted to engage one of the flanges of the rail-base and the other to project over the 80 opposite flange of the rail-base, the first named clip being formed with an underlying seat-support and the other clip with a recess below the plane of said support, a clamping-block arranged within the latter-named clip 85 and having a projection to fit within said recess and extending beneath the adjacent rail-flange, and a wedge adapted to be inserted between said block and the overhanging clip to clamp the rail between the clips. 90 95

4. A rail-fastening comprising a chair provided with a clip to engage one of the base-flanges of a rail, said clip being formed with a recess, a bowed spring-key seated in said recess, said key being formed with projecting 100 end teeth to engage the rail-flange and being confined from longitudinal movement in the recess, and means engaging the opposite side of the rail-flange and co-operating with said clip to secure the rail in position and force 105 the same into engagement with the key.

5. A rail-fastening comprising a chair having a clip to engage one of the flanges of a rail-base, said clip being formed with a longitudinal recess having end stop-shoulders, a 110 bowed spring-key seated within said recess with its convex side inwardly disposed, said key being of greater length than the recess and having terminal teeth projecting therefrom and adapted to engage said shoulders 115 under the pressure of the rail, and means for engaging the other side of the rail-base to clamp the rail between the clips and hold the rail in engagement with the key.

6. A rail-fastening comprising a chair having integral clips arranged respectively to engage and projecting over the flanges of the base of a rail, the plate being provided below said clips with seat portions arranged one below the other, the seat portion below the engaging clip forming a support for the adjacent flange of the rail-base, a clamping-block fitting within the overhanging clip and arranged to bear against the opposite side of the rail, said block having a projection rest- 120 125 130

ing upon the other seat and extending beneath the other flange of the rail, the opposing faces of the block and overhanging clip being concaved to form a tapering circular 5 recess, a correspondingly-shaped key fitting in said recess, and means engaging said key to clamp the block in applied position.

In testimony whereof I affix my signature in presence of two witnesses.
